CLAIM

The ornamental design for a wearable sensor, as shown and described.

DESCRIPTION

FIG. 1 is a front perspective view of another wearable sensor showing the new design;

FIG. 2 is a front view thereof;

FIG. 3 is a top plan view thereof;

FIG. 4 is a bottom plan view thereof;

FIG. 5 is a left side view thereof;

FIG. 6 is a right side view thereof;

FIG. 7 is a rear view thereof;

FIG. 8 is a front perspective view of another wearable sensor showing the new design;

FIG. 9 is a front view thereof;

FIG. 10 is a top plan view thereof;

FIG. 11 is a bottom plan view thereof;

FIG. 12 is a left side view thereof;

FIG. 13 is a right side view thereof;

FIG. 14 is a rear view thereof;

FIG. 15 is a front perspective view of another wearable sensor showing the new design;

FIG. 16 is a front view thereof;

FIG. 17 is a top plan view thereof;

FIG. 18 is a bottom plan view thereof;

FIG. 19 is a left side view thereof;

FIG. 20 is a right side view thereof; and,

FIG. 21 is a rear view thereof.

The broken lines are for the purpose of illustrating portions of the article and form no part of the claimed design.
